DESIGN FOR A STORAGE BATTERY CASE

Oliver O. Rieser, Oak Park, Ill., assignor to The Richardson Company, Lockland, Ohio, a corporation of Ohio

Application April 3, 1935, Serial No. 56,189

Term of patent 7 years

To all whom it may concern:

Be it known that I, Oliver O. Rieser, a citizen of the United States, residing in Oak Park, in the county of Cook and State of Illinois, have invented a new, original, and ornamental Design for a Storage Battery Case, of which the following is a specification, reference being had to the accompanying drawing, forming part thereof.

In the drawing, the figure is a perspective view

of a storage battery case, showing my new design. The side and end of the storage battery case not shown in the drawing bear substantially the same design as the side and end illustrated.

I claim:

The ornamental design for a storage battery case, as shown and described.

OLIVER O. RIESER.
